U.S. patent application Ser. No. 10/313,797, Shimizu, filed Dec. 6, 2002.

Primary Examiner—Louis S. Zarfas*Assistant Examiner*—Robert A. Delehanty(74) **Attorney, Agent, or Firm**—Ladas & Parry(57) **CLAIM**

The ornamental design for “bathtub”, as shown.

DESCRIPTION

FIG. 1 is a front view showing the design of this invention;

FIG. 2 is a back view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.
